LAZARD KAHN AND RUDOLPH THIEM, OF HAMILTON, OHIO, ASSIGNEES TO
F. & L. KAHN & BROTHERS, OF SAME PLACE.

DESIGN FOR A HEATING-STOVE.

Design No. 17,718, dated September 13, 1887.

Fig. 2.

Fig. 1

UNITED STATES PATENT OFFICE.

LAZARD KAHN AND RUDOLPH THIEM, OF HAMILTON, OHIO, ASSIGNORS TO
F. & L. KAHN & BROTHERS, OF SAME PLACE.

DESIGN FOR A HEATING-STOVE.

SPECIFICATION forming part of Design No. 17,718, dated September 13, 1887.

Application filed August 2, 1887. Serial No. 245,983. Term of patent 7 years.

To all whom it may concern:

Be it known that we, LAZARD KAHN, a citizen of the United States, and RUDOLPH THIEM, a subject of the Emperor of Germany, residing 5 in Hamilton, Butler county, Ohio, have invented certain new and useful Improvements in Designs for Stoves, of which the following is a specification, reference being had to the accompanying print, forming a part hereof, in 10 which—

Figure 1 is a perspective view of a stove embodying our design, and Fig. 2 a face view of one of the side panels of the flame-section.

The leading features by which our design is 15 characterized are as follows:

The flame-section A has its sides embellished by the panels B, ornamented by the figure of a girl with musical instruments, surrounded by fanciful foliage carving, and its front, at each 20 side the door opening, embellished by fanciful torches C.

The deflecting-ring D between the fire-section and the flame section is concentric with the flame-section at the front and back of the 25 stove, and at the sides of the stove is ornamented by outwardly-projecting lobes E.

The fuel-door F is ornamented by an arch top having fancifully-beaded arch and chord moldings, the arch top having a central quarterfoil 30 opening flanked by triangular openings and radiating foliate-work, the door having also a central rectangular three-part panel, the end portions of this three-part panel being embellished by filleting, forming a vertical series of 35 three interlaced diamonds, and by ornamental double-ended scrolls above and below the fillet-work.

The legs G present a mitered corner embellished by beading, the side faces of the leg being embellished by foliate-work merging into 40 claws at the foot of the leg.

We claim—

1. A design for a stove, as herein shown and described, embodying the flame-section A, 45 having its sides embellished by the panels B, ornamented by the figure of a girl with musical instruments, surrounded by fanciful foliage carving, and its front, at each side the door-opening, embellished by fanciful torches C, the 50 deflecting-ring D, concentric with the flame-

section at the front and back of the stove, ornamented at the sides of the stove by outwardly-projecting lobes E, the fuel-door F, ornamented by an arch top having fancifully-beaded arch and chord moldings, the arch top 55 having a central quarterfoil opening flanked by triangular openings and radiating foliate-work, the door having also a central rectangular three-part panel, the end portions of this three-part panel being embellished by filleting, forming a vertical series of three interlaced diamonds, and by ornamental scrolls above and below the fillet-work, and the legs G, presenting mitered corners embellished by 60 beading, the side faces of the legs being embellished by foliate-work merging into claws at the foot of the legs.

2. In a design for stoves, the flame section A, having its sides embellished by the panels B, ornamented by the figure of a girl with 65 musical instruments, surrounded by a fanciful foliate carving, and its front, at each side the door-opening, embellished by fanciful torches C, as shown.

3. In a design for stoves, the deflecting-ring 70 D, concentric with the flame-section at the front and back of the stove, and ornamented at the sides of the stove by outwardly-projecting lobes E, as shown.

4. In a design for stoves, the fuel-door F, ornamented by an arch top having fancifully-beaded arch and chord moldings, the arch top having a central quarterfoil opening flanked by triangular openings and radiating foliate-work, the door having also a central rectangular 75 three-part panel, the end portions of this three-part panel being embellished by filleting, forming a vertical series of three interlaced diamonds, and by ornamental double-ended scrolls above and below the fillet-work, as 80 shown.

5. In a design for stoves, the legs G, presenting mitered corners embellished by beading, and faces embellished by foliate-work merging into claws at the foot of the legs, as shown.

LAZARD KAHN.
RUDOLPH THIEM.
